INNER SPRING MATTRESS

Edward D. Leeman, Medford, Mass.

Application May 6, 1933, Serial No. 669,768

1 Claim. (Cl. 5—260)

This invention relates to inner spring mattresses and has for its general object to provide an inner spring construction for an inner spring mattress which has novel reinforcing means at the edges serving to reinforce and strengthen the edges of the mattress.

Fig. 1 is a fragmentary plan view of a portion of an inner spring for a mattress embodying my invention;

Fig. 2 is a fragmentary sectional view of an inner spring mattress embodying my invention, the section through the inner spring structure being taken on the line 2—2, Fig. 1;

Fig. 3 is a perspective view of one of the reinforcing elements employed for reinforcing the edge of the mattress.

In the drawing 1 indicates a portion of an inner spring mattress which includes as usual an inner spring structure indicated generally at 2 and which is enclosed within an envelope 3 of padding material which may be cotton or curled hair or any other suitable fibrous material which is commonly used for mattresses.

The present invention relates to the inner spring construction. This inner spring comprises a plurality of vertical double conical springs 4 which are preferably arranged closely together as shown.

The top and bottom coils of adjacent springs are tied together in any suitable way as by means of tie wires 5. The spring structure is also provided with upper and lower binding wires 6, 7 which surround the spring structure. The upper binding wire 6 is in contact with the upper turns 8 of the marginal springs 4 and is secured to such turns while the lower binding wire 7 is similarly in contact with the lower turns 9 of such marginal springs.

The binding wires are tied to the top and bottom turns 8 and 9 of the marginal springs in some suitable way and as herein shown this is accomplished by means of a tie wire 10 which is wound about each binding wire and some of the turns of which, such as the turns 11, enclose also the upper and lower turns of the springs 4.

In order to reinforce the edge of the spring structure 2, I have employed reinforcing elements having the construction best shown in Fig. 3. Each of these reinforcing elements is made of wire which is bent to form two connected V-shaped members 12, the legs of each member being resiliently connected at the apex of the V and the ends of the legs being attached to the binding wires 6 and 7.

In making the reinforcing member a length of

wire will be bent to form the two V-shaped members 12 each member having the coil 14 at the apex of the V and the leg 15 of each member connected to the similar leg of the other member through a connection 16 which constitutes the central portion of the wire from which the reinforcing member is made. The leg 17 of each V-shaped element 12 has the laterally-extending wire end 18 which extends parallel to the portion 16, the two wire ends 18 being in alignment with each other and preferably meeting each other. The two extremities of the wire are bent inwardly as indicated at 19, said inwardly-bent ends abutting each other.

The wire which is used for this reinforcing member is resilient and the presence of the coils 14 at the apex of each V-shaped member provides a resilient connection between the legs 15 and 17 of each V-shaped member which permits the legs to move toward each other but which tends to separate the legs.

The portion 16 of each reinforcing member lies in contact with one of the binding wires and is secured thereto while the parallel portions 18 are in engagement with the other binding wire and are similarly secured thereto. These portions 16 and 18 of each reinforcing member may be secured to the binding wires in any approved way but I will preferably employ the tie wire 10 for this purpose, certain of the turns 20 of the tie wire encircling both the binding wire and the engaging portion 16 or 18 of the reinforcing member.

Each reinforcing member is constructed so that the length of the portion 16 is equal to the spacing of the springs and the reinforcing elements are secured to the binding wires so that the V-shaped members 12 will be situated between adjacent coils 4 as best seen in Fig. 1.

In assembling the parts one reinforcing element 40 will be placed in position with the two V-shaped members 12 thereof embracing one of the springs 4 and the next reinforcing element will be placed in position so that its V-shaped members 12 will embrace the second spring 4 from the spring 45 which is embraced by the first-named reinforcing element. Thus these reinforcing elements will be positioned so as to embrace the alternate marginal springs 4.

These reinforcing elements are so made that normally the arms 15 and 17 of each V-shaped member tend to separate a distance somewhat greater than that they occupy in the mattress and as a result under normal conditions the tension or resiliency of the reinforcing elements 55

exerts a separating force on the binding wires 6 and 7. When a weight is applied to the edge of the mattress, as for instance if a person sits on the edge of a mattress, the edge springs will, 5 of course, be compressed and these reinforcing elements import into the mattress additional resistance to such weight and thus serve to prevent the edge of the mattress from collapsing unduly.

I claim:

- 10 10 An inner spring structure for an inner spring mattress comprising a group of vertical springs, a binding wire encircling the group of springs at both top and bottom and secured to the top and bottom turns of each marginal spring of 15 the group, and a plurality of reinforcing elements connecting the upper and lower binding wires at a plurality of points, each reinforcing element being made of a single length of wire bent to present two integrally-connected V-shaped portions occupying parallel planes with the legs of each V-shaped portion of equal length and integrally but resiliently connected at the apex of 20 the V-shape and with the opposite ends of the

corresponding legs of the two V-shaped portions integrally connected by a connecting portion extending at right angles to the legs and integral with each leg, said single length of wire being further bent to form an arm extending laterally 5 from the opposite end of the other leg of each V-shaped portion, said arms being parallel with the connecting portion and in alignment with and meeting each other, the apexes of the two V-shaped portions being unconnected, said connecting portion having substantially the same 10 length as the diameter of each vertical spring, a reinforcing element being placed with its two V-shaped members embracing alternate marginal vertical springs along the side of the mattress 15 whereby there will be a V-shaped portion between each two adjacent springs along said side of the mattress, means tying the connecting portion of each reinforcing element to one of the binding wires and means tying the two arms of 20 each reinforcing element to the other binding wire.

EDWARD D. LEEMAN.
